UNITED STATES PATENT OFFICE.

WILLIAM H. LEHMANN, OF O'FALLON, ILLINOIS.

DESIGN FOR A MOP HOLDER AND DRIER.

41,366.

Specification for Design.

Patented May 9, 1911.

Application filed March 6, 1911. Serial No. 612,714. Term of patent 7 years.

To all whom it may concern:

Be it known that I, WILLIAM H. LEHMANN, a citizen of the United States, residing at O'Fallon, St. Clair county, in the State of Illinois, have invented a new, original, and ornamental Design for a Mop Holder and Drier, of which the following is a specification, reference being had to the accompanying drawing, forming part thereof.

The figure is a perspective view of a mop holder and drier constructed according to my design.

I claim:

The ornamental design for a mop holder and drier, as shown.

WILLIAM H. LEHMANN.

Witnesses:

E. L. WALLACE,
N. G. BUTLER.
